Primary Examiner — Jack Reickel*Assistant Examiner* — Bobby W Jones, II(74) Attorney, Agent, or Firm — Design IP(57) CLAIM

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of portions of the beverage container is for the purpose of illustrating environmental subject matter and forms no part of the claimed design.

1 Claim, 6 Drawing Sheets(56)
